VICTOR H. CAROUSO, OF OAKLAND, CALIFORNIA, ASSIGNOR TO DUART MANUFACTURING CO. LTD., OF SAN FRANCISCO, CALIFORNIA, A CORPORATION OF CALIFORNIA

REEL

Application filed February 11, 1929. Serial No. 338,936.

The invention relates to reels and more specifically to twin reels adapted to rotate on a common axis in opposite directions and which are particularly adapted to use in a chandelier for the support of electric heaters for treatment of the human hair to impart thereto what is commonly known as a permanent wave.

In the usual hair dressing establishment it is the practice to use a chandelier having a plurality of heaters, usually twenty-four in number suspended from the chandelier by cords for waving the hair. In performing this operation the hair is damped with a suitable solution and separated into wisps which are wound around mandrels, and the mandrels with the hair wound therearound are then placed into heating devices and heat introduced thereto, thereby drying the hair while wound on the mandrel which will result in imparting to the hair a fixed wave after the mandrel is withdrawn from the hair.

An object of the invention is to arrange reels in couplets for the reeling thereon of the supporting cords for the heating devices. The reels are rotatable in opposite directions on a common shaft when dispensing the supporting cord therefrom while their respective directions of rotation are reversed when the supporting cords are reeled in thereon by the action of springs controlling the reels. The arrangement of the reels in couplets on a common shaft results not only in an economical use of space but obviates the necessity for the duplication of elements.

Another object of the invention is to prevent the stress on the supporting cord for the heating device caused by the tendency of the spring actuated reel to re-wind the cord thereon when it has been unwound therefrom for attaching the heating element to the hair.

A further object of the invention is to construct a device of the character indicated, the parts of which in the interest of economy of manufacture may be struck from sheet metal.

For a fuller and more comprehensive understanding of the invention reference may now be had to the following specification specifically describing the invention by ref-

erence numerals taken together with the drawing forming part of this specification and in which like reference numerals indicate like parts throughout the several views of the drawing.

In the drawing, Figure 1 is an elevation of a chandelier with a portion of the drum broken away for more clearly showing the invention as applied thereto.

Figure 2 is a top plan view of one of the twin reels and the restraining pulleys associated therewith.

Figure 3 is a vertical sectional view taken on line 3-3 of Figure 2 looking in the direction indicated by the arrows.

Figure 4 is a detailed end view of one of the restraining pulleys.

Figure 5 is a vertical sectional view of one of the restraining pulleys showing the supporting cord looped therearound.

Figure 6 is a plan view of the washer showing the resilient dog thereon for locking the pulley against rotation in one direction.

Figure 7 is an edge view of the washer showing the dog extending therefrom.

Reference character 10 indicates the base of the chandelier with vertical standard 11 which preferably rotatably supports the drum or housing 12 at the upper end thereof. 13 indicates a bracket U-shaped having inwardly extending arms 14 and 15 which may be suitably secured to the inner face of the peripheral wall 16 in any suitable manner as by rivets 17. Non-rotatably mounted between the arms 14 and 15 of bracket 13 is a

shaft 18 upon which is rotatably mounted twin reels 19 and 20 having therebetween non-rotatable disc 21 which is affixed to shaft 18.

Reels 19 and 20 are provided with hollow hubs 22 and 23 for the reception therein of coiled springs 30, one end of the springs fixedly engaging the shaft 18, with their outer ends suitably engaging the reels 19 and 20 and adapted to exert a rotary movement to the respective reels in opposite directions.

Affixed to the peripheral wall of drum 12 is a dependent bracket 24 having a pulley 25 journaled on shaft 26 fixedly related to the bracket. Pulley supporting cords 17 may be

looped around the pulley which will form

a slip connection for the cord intermediate the reel and the heater and thus act as a brake on the tendency of the reel to re-wind the cord thereon under the urge of the spring 30. 5 Pulley 25 has a circular depression 27 formed in the base thereof for reception of the disc 28 which is affixed to bracket 24, the reduced portion of shaft 26 passing through aperture 33 of the disc 28. Disc 28 has struck upwardly therefrom dog 31 for engagement with detent 32 in the recess 27 of the pulley 25 for the purpose of locking the pulley against rotation in one direction.

It will be readily seen from the description of the pulley 25 with its co-related parts that the supporting cords 17 for supporting the heaters 34 may be rotated in clockwise direction, as viewed in Figure 5, thereby unreeing the cord from the reel but will be prevented from rotating in an opposite or clockwise direction by the urge of the spring actuating the reel and tending to re-wind the cord thereon by reason of the dog 31 engaging the detent 32 in the recess of the pulley. 20 This avoids an undue pulling action on the hair by the heating element which becomes more or less painful as the drying of the hair to set the wave therein requires a more or less lengthy duration of time. 25 This avoids an undue pulling action on the hair by the heating element which becomes more or less painful as the drying of the hair to set the wave therein requires a more or less lengthy duration of time. 30 It will be understood that in order to re-wind the cord upon the reel by the action of the spring it will be but necessary to raise the heater with the hand, thereby relieving the cord of the weight of the heater, which 35 will release the binding action of the cord upon the pulley by reason of the loop there-around and permit the spring to re-reel the cord by causing it to readily slip around the pulley after the loosening of the loop there-around. 40

Having thus described the invention, what I claim is:

1. A reel comprising a housing, a shaft fixed therein, a disc on said shaft, spring operated spools disposed on opposite sides of said disc and rotatable on said shaft, ears depending from said housing and having idler spools mounted thereon, and means for preventing reversal of said idler spools.

2. A reel comprising a pair of spring actuated spools rotatably mounted on a fixed shaft, a disc interposed between said spools, a bracket to support said shaft and depending ears on said bracket having idler spools mounted thereon, recesses in the bases of said idler spools adapted to cooperate with a spring pawl to prevent rotation of said idler spools in one direction.

3. A reel comprising a bracket, parallel arms on said bracket, a shaft fixed between said arms, a disc fixed to said shaft, spring operated spools rotatably mounted on said shaft and disposed on opposite sides of said disc, said spools being adapted for opposite rotation under spring tension, ears depending

from said bracket, a disc fixed to said ears, up struck pawls on said discs, stud shafts centrally disposed in said discs and having rotatably mounted thereon idler spools, a counterbore in said spools for cooperation with said discs, and an arcuate recess in said counterbore for cooperation with said pawls adapted to resist rotation of said idler spools in one direction, and mounting holes in said bracket.

4. A reel for hair waving apparatus comprising a bracket having a pair of spaced arms, means for mounting a pair of spring actuated spools between said arms and on a common axis, said spools being adapted for rotation in opposite directions under spring tension, ears depending from said bracket and being positioned laterally on each side of said arms, idler spools mounted on said ears with the axes thereof transverse to that of the first mentioned spools, and means for preventing turning of the idler spools in one direction.

5. In a device of the character described, a drum, a pair of spaced arms within the drum and secured to the peripheral wall thereof, means for mounting a pair of spring actuated spools between said arms and on a common axis, said spools being adapted for rotation in opposite directions under spring tension, ears depending from said bracket and being positioned laterally on each side of said arms, idler spools mounted on said ears, and means for preventing turning of the idler spools in one direction.

In testimony whereof I have affixed my signature.

VICTOR H. CAROUSO.
